UNITED STATES PATENT OFFICE.

JOHN P. PERASS, OF GLEN ROCK, NEW JERSEY.

WATER HEATER.

Application filed March 10, 1927. Serial No. 174,113.

This invention relates to improvements in water heaters, the principal object of the invention being to provide a system whereby the excess heat from a furnace which is usually carried up the chimney and wasted is made use of to maintain a continuous supply of hot water while the furnace is in operation.

A further object of the invention is to provide a water heater in which not only is the waste heat of the furnace utilized to the best advantage, but provision is made for independently heating the same system by means of a gas burner.

With the foregoing and other objects in view, which will appear as the description proceeds, the invention consists in the novel features of construction and combination of parts which will be more fully described hereinafter and particularly pointed out in the claims.

In the drawing accompanying and forming part of this specification,

Fig. 1 is a partly sectional plan view, with parts broken away, of a device embodying a preferred form of my invention;

Fig. 2 is a side elevation of said device, also with parts broken away and shown in section, the device being shown in this figure provided with independent heating means; and

Fig. 3 is a transverse sectional view, taken on the line 3—3 of Fig. 2;

Similar characters of reference designate the same parts in the different figures of the drawing.

Referring to the drawing, 1 designates a tubular housing, said housing being adapted to form a section of the usual flue that connects a furnace to the smokestack and which serves to lead away the gases of combustion, excess heat, etc. It is the principal object of my invention to utilize a large part of this excess heat, which would otherwise pass up the chimney and be thus entirely wasted, for furnishing a constant supply of hot water so long as the furnace is in operation. To this end, as shown in Figs. 1 to 3, I have provided a series of tubes 2 bent into semi-circular form and each having a straight portion 3 at each end thereof. The tubes 2 are preferably mounted within the flue 1 in spaced and staggered relation; that is to say, one tube is set with its curvature extending in one direction and the next tube with its curvature in the opposite direction. The

straight ends of the tubes pass through diametrically opposite perforations in the wall of the flue, the straight portion at one end of each tube being secured in communication with a manifold 4 connected with a suitable source of water supply (not shown), while the straight portions at the opposite ends of the tubes are in communication with a manifold 5 which may be connected to a suitable reservoir (not shown) for storing the heated water. It will readily be seen that with this construction when the furnace is in operation the water contained in the tubes 2 will quickly become heated and move upwards into the manifold 5 thereby imparting heat to the water in said manifold, which in turn will deliver it to the reservoir for use as desired. In this manner the excess heat developed from the fuel consumed in the furnace, and which heat is usually entirely lost, is made to serve a useful purpose. The flue 1 is preferably divided longitudinally along a plane passing centrally through the perforations through which the ends 3 of the tubes pass, as indicated by the line 1^a in Fig. 1, so that said flue can readily be detached for cleaning or replacement, suitable means being provided for holding the two parts together, such means being shown in Fig. 2 in the form of perforated lugs 1^b adapted to be bolted together, although any other preferred means may be provided.

In connection with the heating device above described, I have also provided means for heating the water by means of gas when the furnace is not in operation. As shown in Figs. 2 and 3, a tubular housing 6 is provided which encloses that portion of the supply manifold 4 in which the ends of the tubes 2 are secured, said housing being provided in its side and end walls with openings 7 and 8 for permitting circulation of air. One portion of the side wall, as 6^a, is hingedly secured at one edge thereof to the other portion to provide a door which may be opened to the position shown in full lines in Fig. 3 to permit lighting and cleaning of the device, said door being adapted to be closed as indicated in dotted lines in Fig. 3 for retaining heat, the door being provided with a suitable rotatable latch 9 for maintaining it in closed position. The housing 6 may be supported in any desired manner. As shown herein it is supported by its end walls on the manifold 4 and also

by brackets 10 riveted to the housing and to the flue 1. A gas tube 11 passes into the housing 6 through one end thereof and is supported therein by brackets 12 depending from the manifold 4, one near each end of the housing 6, said gas pipe having a cap 13 closing the end thereof within the housing and provided at its opposite end with the usual valved connection 14 for regulating the flow of gas. A plurality of perforations 15 are formed along the upper portion of the pipe within the housing for permitting the gas to escape and be ignited in the usual manner.

15 While I have described in detail the forms of the device herein illustrated it is to be understood that I do not intend thereby to limit my invention to the precise features of construction shown, as I am aware that 20 many mechanical modifications may be made therein without departing from the spirit and scope of the invention as set forth in the appended claims.

Having thus described my invention, 25 what I claim is:

1. A water heater, comprising in combination, the smoke flue of a furnace, a series of single longitudinally semicircular tubes disposed within said flue and having their 30 opposite ends extending through the wall of the flue at diametrically opposite points, a water-supply manifold in communication

with the ends of all of said tubes at one side of the flue, and a water-receiving manifold in communication with the opposite ends of all of the tubes. 35

2. A water heater, comprising in combination, the smoke flue of a furnace, a series of single longitudinally semicircular tubes disposed within said flue and each projecting at its opposite ends through the wall of the flue at diametrically opposite points, the curvature of alternate tubes extending parallel with opposite sides of the wall of the flue, a source of water supply communicating with all of said tubes at one side of the flue, and a delivery system communicating with the tubes at the opposite side of said flue. 45

3. A water-heater, comprising, in combination, the smoke flue of a furnace, and a series of tubes disposed within said flue, each of said tubes being bent to follow the curvature of the wall of the flue and having its opposite ends extending through said wall at diametrically opposite points and connected respectively with an intake manifold and an outlet manifold, a housing enclosing said intake manifold, and a gas burner in said housing and adapted to heat the manifold along the length thereof. 50

55 In testimony whereof I have signed my name to this specification.

JOHN P. PERASS.
